CLAIM

We claim the ornamental design for a cartridge refill for a correction tape/glue tape, as shown and described.

DESCRIPTION

FIG. 1 is a front view of the cartridge refill for a correction tape/glue tape;

FIG. 2 is a back view thereof;

FIG. 3 is a left side view thereof;

FIG. 4 is a right side view thereof;

FIG. 5 is a top plan view thereof;

FIG. 6 is a bottom plan view thereof; and,

FIG. 7 is a top and right perspective view thereof.

The broken lines shown in the drawings represent unclaimed portions of the cartridge refill for a correction tape/glue tape and form no part of the claimed design.
